UNITED STATES PATENT OFFICE.

DAY CHANNING McCRAY, OF OSHKOSH, WISCONSIN, ASSIGNOR, BY MESNE ASSIGNMENTS, TO NATHAN PAINE, OF OSHKOSH, WISCONSIN.

IRONING-BOARD CABINET.

Application filed October 26, 1923. Serial No. 670,894.

The invention relates to ironing board cabinets.

An object of the invention is to provide a device of this character in which one or more ironing boards are mounted to be lowered to a rigid operative position from a concealed and compact closed position within a housing frame built into a wall.

A further object of the invention is to simplify the swinging and locking mechanism for the boards and to perfect details of construction generally.

With the above and other objects in view the invention consists in the ironing board cabinet as herein claimed and all equivalents.

In the drawings: Fig. 1 is a perspective view of a device embodying the invention built into a wall and with the parts in their open position; Fig. 2 is a front elevation of 20 the device before being installed and with the parts in their closed position, parts being broken away and parts being shown in section; Fig. 3 is a vertical sectional view taken on the line 3—3 of Fig. 2; Fig. 4 is a 25 view similar to Fig. 3 but with the parts in their open position; Fig. 5 is a fragmentary detail view of one of the iron boards, parts being broken away and parts being shown in section, and Fig. 6 is a fragmentary detail view of one side of the housing frame, parts being shown in section.

In the drawings the numeral 10 designates a vertical rectangular housing frame closed at the rear by a panel 11, preferably of veneer. The frame 10 is built of uprights 12 rigidly secured in spaced relation by cross members 13 and the panel 11.

The frame is built into a wall and provided with a casing 14 on which is hinged a 40 door 15 as seen in Fig. 1. When the device is not in use the door is held closed by a latch 16.

An ironing board 17 of usual shape has one end formed with a groove 18 in which is 45 saddled a cylindrical rod 19 secured by screws 20 to the board, as seen in Fig. 5. The ends of the rod 19 project beyond the edges of the board to form trunnions 21 which are fitted with metal ferrules 22. The 50 trunnions 21 are constrained to move in aligned guides which are preferably grooved 23 routed out of the inner faces of the uprights 12 of the housing frame 10.

In the closed position of the device, as

seen in Fig. 3, the trunnions 21 rest in the 55 lower ends 24 of the vertical portions 25 of the grooves 23, and the board is retained in a vertical position by its engagement with a spring clip 26 fastened to one of the uprights 12 and by a transverse support 27 60 secured between the uprights 12, which limits its rearward movement.

When it is desired to bring the board 17 from its closed position as seen in Fig. 3 to its open position as seen in Fig. 4 it is released from the spring clip 26 and swung forwardly about its trunnions 21, which pivot in the lower ends 24 of the guide grooves 23 for a part of the movement. The trunnions are then moved upwardly in the vertical portions 25 of the guide grooves simultaneously with a further forward and downward movement of the board 17. When the trunnions reach the upper ends of the vertical portions of the guide grooves the board 70 75 80 85 90 95 100 105 17 is pushed inwardly and downwardly to move the trunnions along angled inclined portions 28 of the guide grooves 23, as shown by the dotted line position in Fig. 6, the transverse support 27 having an inclined upper face 29 aligned with the lower edge of the inclined portions 28 of the guide grooves. The outer end of the board is then lowered to rock the inner end on the forward upper edge 30 of the transverse support 27 until the trunnions seat in pockets 31 at the rear ends of the angled portions 28 of the guide grooves. This last movement brings the board into a horizontal position with the trunnioned end held against vertical displacement by its engagement with the forward upper edge 30 of the transverse support 27 and the lower face 32 of a transverse support 33 immediately above the pockets 31, which cooperate with the transverse supports 27 and 33 to prevent lateral movement of the trunnions.

The pockets 31 have been shown in the form of concave recesses for receiving the rounded trunnions of the ironing board 17, 100 the recesses being defined at their forward edges by depending projections or abutments forming the upper edges of the laterally extending portions of the trunnion guide grooves, and these depending projections or abutments, together with the upper edge 30 of the lower support 27, which is spaced downwardly and forwardly there-

from to form a lower abutment, permit the board to be introduced between the supports 27 and 33 only when it is longitudinally and rearwardly inclined, since the vertical distance between the edge 30 and the abutments superposed thereabove is made less than the thickness of the board. After passing the upper depending abutments, the trunnions may rise behind them into the pockets or concave recesses 31 when the board is rocked on the edge 30 to a horizontal extended position, as above noted.

To support the board 17 in its horizontal position arms 34 are pivoted by dowels 35 to a cleat 36 secured transversely of the board intermediate its ends and forming a bracket member. The arms 34 are held in spaced relation by cross pieces 37 to form a rigid frame 38 and are inclined to bring their lower ends into abutment with a transverse support 39 secured between the uprights 12 of the housing frame and preferably adjacent one of the cross members 13.

The lower ends of the arms 34 are guided into abutment with the transverse support 39 by a metal rod 42 passing through slots 43 in the arms 34 and secured between the uprights 12 of the housing frame.

In order to relieve the dowels 35 of thrust the upper ends 40 of the arms 34 are rounded to bear in sockets 41 formed in the cleat 36, as seen in Figs. 2 and 4.

The board 17 is brought to its closed position by lifting the free end to the inclination shown in dotted lines in Fig. 6, whereupon it is withdrawn to bring the trunnions 21 to the upper ends of the vertical portions 25 of the guide grooves 23, from which position the trunnions descend to the lower ends of the guide grooves simultaneously with an upward swinging movement of the board to its vertical position against the transverse support 27 and into engagement with the spring clip 26.

A sleeve board 44 has one end provided with ferruled trunnions 45 similar to those on the board 17. The trunnions are journaled in aligned recesses 46 in the uprights 12 at a suitable height above the transverse support 33 and to the rear of the closed position of the board 17.

In the closed position of the device as seen in Fig. 3, the sleeve board 44 is held in a vertical position by its engagement with a spring clip 47 secured to the rear panel 11.

In the open position of the device as seen in Fig. 4, the sleeve board 44 when in use is supported in a horizontal position above the board 17 by a brace member 48 pivoted to bracket 49 secured to the underside of the board, the lower end of the brace member 48 being in abutment with a step 50 in the transverse support 33. The board 17 holds the garments off the floor in a convenient loca-

tion adjacent the sleeve board 44 when it is in operative position. When not in use during the course of an ironing the sleeve board may be easily swung back out of the way to a vertical position.

The two lower cross members 13 and the uprights 12 form a compartment 51 in which the iron and other equipment may be stored when not in use.

The device of the present invention is of simple and compact construction, requiring but little room for its installation. The cabinet is kept to a reasonable height so the device does not become unwieldy to operate. The boards lock into position rigidly with very little manipulation and but few moving parts are required.

What I claim as my invention and desire to secure by Letters Patent is:

1. In an ironing board cabinet, the combination of a frame including spaced uprights provided with guide channels having substantially vertical portions and laterally projecting portions at their upper ends extending and inclined rearwardly and terminating in upwardly projecting pockets, an ironing board having trunnions at one end movable in said channels, a board support disposed immediately below said inclined portions of the guide channels and permitting longitudinal movement of the board at said inclined portions of the guide channels only when the board is rearwardly inclined and said support forming a fulcrum on which the board may be swung to move said trunnions upwardly into said recesses at the rear of said inclined portions of the guide channels for bringing the board to a horizontal position against displacement, and means for retaining the board in upright position within the frame with the trunnions below said support.

2. In an ironing board cabinet, the combination of a vertical housing frame adapted to be secured within a building wall including spaced uprights provided with guide grooves having substantially vertical portions and laterally extending upper portions inclined rearwardly and downwardly and terminating in upwardly projecting pockets, an ironing board having trunnions at one end movable in the guide grooves, means for locking the board in a horizontal position with the trunnions in the pockets including a support mounted in the housing-frame engaging the underside of the board forward of the trunnions and a brace member pivoted to the board intermediate its ends having its lower ends in abutment with a stop mounted in the housing frame, and means for retaining the board in a substantially vertical position within the frame with the trunnions at the lower ends of the guide grooves.

3. In an ironing board cabinet, the com-

bination of a frame adapted to be secured within a building wall and including spaced uprights and spaced transverse supports at an intermediate portion disposed one above and rearwardly of the other, said frame having a pair of upwardly projecting pockets adjacent the ends of the upper transverse support and defined at their forward edges by depending abutments, an ironing board longitudinally movable at one end between said uprights and constrained by said lower support and said abutments to enter between said supports in a rearwardly inclined position, projecting parts on said board adjacent its inner end adapted to enter said pockets from below, for locking the board in a horizontal position with said projecting parts in said pockets and with the transverse supports engageable on opposite sides of the inner ends of said board, and means for retaining the board in upright position within the frame in front of

said supports and with its inner end below said supports.

4. In an ironing board cabinet, the combination of a frame including spaced uprights, an ironing board mounted between said uprights and adapted to be moved to a horizontal operative position, a bracket member secured below said board intermediate its ends, a brace member pivotally mounted on said bracket member and having its lower end longitudinally slotted, a stop mounted in said frame against which the lower end of said brace member is adapted to abut when the board is in horizontal position, and a rod secured transversely of the frame and passing through the slotted lower end of said brace member whereby said end is guided into abutment with the said stop when the board is brought to horizontal position.

In testimony whereof I affix my signature.

DAY CHANNING McCRAY.
